REED

Stephen J. Lucas, Chicago, Ill.

Application January 28, 1942, Serial No. 428,527

2 Claims. (Cl. 84—383)

This invention relates to a reed for wind instruments and is an improvement over my Patent #2,319,419 issued May 18, 1943.

The particular object of this invention is to provide a reed of definite structural features and dimensions which can be produced in dies from plastics and mounted in accurate coacting position on the mouth pieces of instruments, to produce sound waves of improved quality and amplitude with the least expenditure of energy.

Other objects and benefits will be disclosed in the following description and drawings in which:

Fig. 1 is a bottom plan view of my new improved reed and is for a baritone saxophone with dimension lines in dotted outline as will later be explained;

Fig. 2 is a similar bottom plan view of my improved reed for E flat clarinet with dotted dimension lines;

Fig. 3 is a side elevation view of a reed for E flat alto saxophone with dimension lines;

Fig. 4 is a side elevation view of my special mouth piece and associated reed showing the coacting assembly features which will later be explained; and

Fig. 5 is a bottom plan view of the mouth piece and reed shown in Fig. 4.

Now referring to the drawings and in the outset to Figs. 1 and 2 I show bottom plan views of my reeds with dimension lines in dotted outline. At the right hand side of the drawings I show the thickness of the reed on the top of the dotted outline dimension lines. At these points indicated by A to E inclusive, the thickness dimension of the reed is clearly indicated by dimensions in inches. At the left hand side of the figure, I show the dimensions at the rear or outside edges of the dimension lines by the designations Ar to Er. It will be noted that the dimensions A to E are exactly similar, and therefore the reed is of the same thickness along the dotted dimension lines as shown. It will be further noted that the longitudinal distances marked L—1 to L—5 are considerably shorter than the edge dimensions marked Lr—1 and Lr—5. It will be appreciated that the central tongue section F outlined by the dash lines radiating from the V-shaped bridge is considerably shorter than the side sections S although all the tongue sections have exactly similar thickness dimensions as indicated by the dotted dimension lines. This has the effect of creating one central vibrating tongue section and dual vibrating side sections which vastly increases the vibrating areas and produces sound waves of

improved quality and amplitude with the least expenditure of energy.

Many attempts have been made in this art to produce reeds from plastics, but such attempts, in the experience of this applicant, have neither produced satisfactory results nor attained any commercial success. It will be appreciated that reeds made from plastics unlike reeds made from natural wood fibers have a homogeneous uniform structure with physical properties accurately within the control of the manufacturer. When the proper principles of reed construction are understood and applied, reeds of uniform quality and effectiveness can be manufactured, provided that the dimensions are held within $\frac{1}{1000}$ of an inch, and the physical properties of the plastics are uniformly maintained. In like manner reeds may be made of metal such as aluminum or stainless steel, due consideration being given to the physical properties of the metal. I have succeeded in producing reeds of uniform quality and pitch as has been amply proven by laboratory tests and field trials. Because of this uniformity in my reeds, I am able to fix the reed in definite 10 relationship on the mouth piece, and for this purpose I provide the key slot, Ks, as shown in Fig. 1 which coacts with the key, K, as shown in Fig. 4, to assemble the reed and mouth piece in accurate relationship as shown in Fig. 5, and as will 15 later be more fully explained.

Now referring to Fig. 2, I show a similar bottom plan view to Fig. 1, only in this instance I illustrate an E flat clarinet reed. This reed is much smaller than the baritone saxophone reed shown in Fig. 1, as indicated by the relative size of the figures. Similarly to Fig. 1, I have shown the thickness dimensions of the tongue portion of the reed by the dimensions A to F in the center, as compared to the dimensions Ar to Fr on the sides. It will be noted that the same or similar 20 proportions of the dimensions L and LR exist and that by such proportions and dimensions I am enabled to construct a uniformly accurate and effective E flat clarinet reed.

Now referring to Fig. 3, I show a side elevation view of an E flat alto saxophone reed and have indicated by dimensions, the proportions of the elements whereby an E flat alto saxophone reed 25 may be produced.

Now referring to Fig. 4, I show my special mouth piece M having an upstanding key, K, on the bottom face reed to fit the key slot, Ks, in a standard form of my plastic reed, R.

When the mouth piece and reed are assembled 30 as shown in Fig. 5 it will be appreciated that the

key, K, and key slot, Ks, will hold the reed in a definite fixed relationship with the mouth piece "M." The reed is thus held in clamped fixed position by a connector clamp or ligature over the surface of the reed and mouth piece as defined by the area between the dash lines by the dimension C. It will be appreciated that the clamp bearing on the base of the reed as defined by the area "C" permits the tongue of the reed to be free over the opening O in the mouth piece as is well understood in the art. However, in order to produce the best results I have made the opening in my mouth piece, M, with a base projection, Op, for the purpose of assisting diversion of the side-wise air currents as are developed by reeds constructed in accordance with the principles of my invention.

I have discovered that with plastic reeds properly manufactured from accurate dies embodying the principles of my invention it is advantageous to accurately lock the reed in relationship to the mouth piece and that by so doing uniform results are attained giving improved quality and amplitude of tone with less expenditure of energy.

Having thus explained my invention I now claim as new:

1. In a reed for musical instruments, a relatively thick stiff base portion, a tongue, a bridge stiffener section extending from the base into the tongue, the arrangement providing a relatively short active front tongue section and dual coacting active side sections, with all three active sections tapering smoothly outwardly from about .045 inch at the bridge to about .006-.008 inch at the edges for plastic reeds, and key means integral with the reed to position the reed in positive relationship with an associated mouth piece.
2. In a reed for musical instruments, a relatively thick stiff base portion, a tongue, a pointed outwardly tapering bridge stiffener section extending from the base centrally into the tongue, the arrangement providing a relatively short active front tongue section and dual coacting active side sections, with all three active sections tapering smoothly outwardly from about .045 inch at the bridge to about .006-.008 inch at the edges for plastic reeds, said dimensions being proportioned to the physical properties for metallic reeds, and key means integral with the reed to position the reed in positive relationship with an associated mouth piece.

STEPHEN J. LUCAS.
